UNITED STATES PATENT OFFICE.

ADOLF WELTER, OF KREFELD-PZEINHAFEN, GERMANY.

PROCESS FOR THE MANUFACTURE OF HIGH-PERCENTAGE, NONDECOMPOSABLE, DURABLE SOAP.

No Drawing.

Application filed January 8, 1923. Serial No. 611,500.

To all whom it may concern:

Be it known that I, ADOLF WELTER, citizen of the German Empire, residing at Krefeld-Pzeinhafen, Germany, have invented new and useful Improvements in a Process for the Manufacture of High-Percentage, Nondecomposable, Durable Soap, of which the following is a specification.

The soap industry has endeavoured in the last few years to put on the market soaps of as high a percentage of saponification as possible, which shall not be friable and which shall be durable, in powder or solid form.

15 The oldest but also the most expensive process of manufacture for the said purpose consists in this that fluid soap is cooled into slabs which are cut off in small pieces and dried until the product is capable of being ground. This process requires much time, heat and power.

Another process consists in this that more or less concentrated soap solutions are mixed with calcined soda, the reaction mass 25 is cooled and ground. By this process, alkaline soaps are obtained which destroy the textile fibres, and in the case where blocks are pressed from the powder so obtained, these blocks disintegrate in a short time and 30 become simply soda decompositions. The soaps so obtained cannot be manufactured with high contents of fatty acids. In order to render this possible, it has also been tried to mix pulverized resins or stearin 35 with calcined soda and to press the mixture, if required, into briquettes. In this manner, however, soaps are obtained which still contain a high percentage of unsaponified stearic acid or resin.

40 It has, further been attempted to heat castor oil fatty acid in an iron vessel provided with a stirring mechanism and to add calcined soda slowly until everything is saponified and the carbonic acid is driven off. This process can only be used for castor oil fatty acids and since these castor oil soaps have no importance whatever for washing purposes and are to expensive, this process of soap manufacture has not become 45 of practical importance. With all other fatty acids under similar circumstances, bady mixed lumpy masses would be obtained which contain partly a strong excess of soda and partly free fatty acids.

The inventor has now found out that if 55 molten fatty acids are intimately mixed in the neighbourhood of the melting temperature of the fatty acids with definite quantities of calcined soda in powder form, an absolutely homogeneous mass is obtained 60 which becomes heated after a short time and forms a completely saponified, highly concentrated soapy mass which does not contain any more soda. If the double quantity of soda which is necessary for saponification 65 is not exceeded, then the process is carried out in such a manner, that quantitatively more or less water free sodium soaps and sodium bicarbonate are formed. These have no alkaline reaction and may be used for wool, 70 silk and also for the human skin. They can also be suitably hardened and cooled, and after cooling easily pulverized. The most important point however is that the blocks which are pressed from the powder last indefinitely, do not burst and do not show any 75 soda decompositions. The process is carried out in such a manner that the fatty acids are heated in apparatuses having a stirring device, a little above the melting point, and a molecule of calcined soda is added to a molecule of fatty acid until everything is mixed to form a homogeneous mass. This mass is allowed to become heated by the heat which itself generates until a sample taken 80 does not give any unsaponified fatty acids with ether, whereupon either the mass which is still hot is formed into bands or extrusions, or the cooled mass is ground and the soap so obtained is put on the market either 85 as such or pressed into briquettes or blocks. 90

It is also possible to replace one part of soda by potash and a part of the fatty acids by resin. It is also possible to add fat dissolving means to the fatty acids, whereby the process is carried out equally well and whereby particularly effective washing means are obtained. The heating generated varies according to the fats used. With oxidizable fats the heating may be generated 95 by simultaneous oxidation until the carbonization takes place, in which case care should be taken that the mass to be cooled shall be well spread out. The lower the temperature of the fatty acids, the more uniform is 100 the mixture, and the smaller is the quantity of carbonic acid which is developed in the reaction mass so that only the sodium salt 105

of the fatty acids and sodium bicarbonate are formed.

Usually the finer and the more free of water the calcined soda used, the easier it is to carry the process out. It has been shown that with not too large contents of calcined soda absolutely homogeneous and completely saponified products are obtained which are capable of being ground and shaped, which do not show any decomposition and the duration of which is unlimited.

Example 1.

1000 kgs. of olein of an acidity number of 15 200 are given into a vessel provided with a stirring mechanism at a temperature of 30 to 35° C., and 200 to 250 kgs. of well-ground calcined soda are added, whereby an entirely homogeneous thin pulp is obtained. 20 When after a short stirring, the latter has become sufficiently viscous so that it cannot be unmixed again, the reaction mass is allowed to settle on sheets of iron which are placed in drying chambers. The soapy pulp 25 becomes then puffed up during the next few hours according to the quantity of soda which is used owing to the formation of carbonic acid and produces a hard, porous, homogeneous soapy mass. This mass can be 30 easily pulverized and dissolves easily and clearly in pure water, developing a strong lathering and high cleansing power. If only one molecule of water-free soda is used for two molecules of fatty acids, then when it is 35 worked in small quantities a subsequent heating in driving chambers is necessary under certain circumstances for driving off the carbonic acid. In all cases, however, where a small excess of soda, and when one 40 molecule of soda is used for one molecule fatty acid such a strong heating is generated by the formation of bicarbonate that complete saponification takes place after a short time. The end of the reaction is to be recognized by this that a sample taken being pulverized does not give any fatty acids with ether.

Example 2.

50 1000 kgs. of fluid palm nut oil acid of an acidity of 250 is added in a steady stream at a temperature of 35° C. into a mixing drum having a good stirring mechanism, in which 450 to 500 kgs. of calcined soda have been 55 previously introduced. A thin pulp is then obtained which becomes heated by the saponification which takes place, and becomes thicker and can finally be removed from the mixing vessel as an entirely homogeneous, 60 hard friable mass. On the following day, the reaction mass which has been formed is so hard and brittle that it can be easily ground, does not feel fatty to the touch, and consists only of a mixture of soap and bicarbonate, which forms a clear solution with

water and has high lathering and cleansing properties.

Example 3.

1000 kgs. of fluid distilled cotton oil, fatty acid (soap stock fatty acid) of an acidity number 202 are mixed in a mixing drum having a strong stirring mechanism, with 400 kgs. of dried calcined soda at about 30° or 35° C. When the mass has become like a pulp and does not stick any longer, it is pressed by a screw lying at the bottom of the mixing vessel into an extrusion press and shaped either hydraulically or mechanically 70 into extrusions of any suitable diameter. These, after a short time, by the complete saponification which takes place, become hard and brittle, have a good appearance 75 and a long duration.

In this process, it is possible by using suitable apparatus to manufacture soaps in a continuous manner. The mode of working from the moment of the introduction of the fluid fatty acids until the outlet of the hard, saponified, saleable product, requires 80 according to the temperature and to the kind of fatty acid, from a quarter of an hour to an hour.

Example 4.

1000 kgs. of molten cocoa nut oil fatty acid of an acidity number 255 are stirred together with 600 kgs. of calcined soda which contains 20% of water and is ground very finely into a mixing drum, whereby 100 after a certain time the mass hardens into a dough, becomes warm afterwards and then becomes completely saponified. When the mass does not stick any longer, it is shaped by means of an extrusion press into noodles or is ground after cooling and pressed into blocks. The blocks which are so obtained do not contain any more soda, but only bicarbonate and a little water. They do not 110 burst, their duration is unlimited, and do not show any signs of decomposition even after one or more years of storage.

Example 5.

115 1000 kgs. of fluid, distilled cotton oil, fatty acid (soap stock fatty acid) of an acidity number 202 are mixed with 50 kgs. of turpentine oil, whereupon this mixture is mixed in a mixing drum having a strong stirring mechanism with 400 kgs. of dried calcined 120 soda at approximately 30° C.

When the mass has become like a dough and does not stick any longer, it is pressed by a screw lying at the bottom of the mixing vessel into an extrusion press, and shaped either hydraulically or mechanically 125 into extrusions of any suitable diameter. These become hard and brittle in a short time, owing to the complete saponification that takes place, and have a good appearance 130

and a long duration. It is, of course, possible to allow the mass to cool, to grind it into a fine powder, and if necessary to press it into blocks. Instead of 50 kgs. of turpentine oil, it is possible to use according to the same process, 100 kgs. of carbon tetrachloride or 100 kgs. of benzol or its homologues.

I claim:

- 10 1. A process for the manufacture without the addition of water of non-decomposable soap of high fatty acid content, by mixing at the temperature of the approximate melting point of the fatty acids, a measured quantity of water free alkaline carbonate with commercial fatty acids, said measured quantity being approximately double the quantity required for the complete saponification of said fatty acid, and said excess 20 of alkaline carbonate being approximately the quantity necessary for the absorption by said excess of all the carbon dioxide resulting from said saponification whereby a soap is formed containing a substantial excess of the bicarbonate of said alkali and approximately no stronger alkaline impurities than said bicarbonate of soda.
- 25 2. A process for the manufacture without the addition of water of non-decomposable soap of high fatty acid content, by mixing with commercial fatty acids at the temperature of the approximate melting point of

the fatty acids, an excess of a water free alkaline carbonate over the normal amount required for saponification of said fatty acid, said excess being retained in intimate mixture with said saponifying fatty acid to absorb the carbon dioxide liberated by said saponification and permitting the mixture as herein noted to stand until a soap with 40 a substantial quantity of the bicarbonate of said alkali is formed and in which only traces of the carbonate of said alkali remain.

3. A process for the manufacture without the addition of water of non-decomposable soap of high fatty acid content in powdered or solid form, by mixing at the temperature of the approximate melting point of selected fatty acids, an excess of anhydrous alkaline carbonate over the normal amount required 45 for saponification of said selected fatty acids, retaining said excess in intimate mixture with said saponifying fatty acid to absorb the carbon dioxide liberated by said saponification and permitting the mixture 50 as herein noted to stand until a soap with a substantial quantity of the bicarbonate of said alkali is formed and in which only minute traces of the carbonate of said alkali remain.

In testimony whereof I have signed my name to this specification.

DR. ADOLF WELTER.
